UNITED STATES PATENT OFFICE

CORNELIS F. M. VAN BERKEL, OF WASSENAAR, NETHERLANDS, ASSIGNOR TO U. S. SLICING MACHINE COMPANY, OF LA PORTE, INDIANA, A CORPORATION OF INDIANA

SLICING MACHINE

Application filed June 14, 1928, Serial No. 285,346; and in Great Britain June 28, 1927.

This invention relates to machines for slicing meat and other substances and refers to conveyers used, or intended for use, in association with such machines for the purpose of removing the slices from the knife as they are cut thereby and carrying them to a position in which they can be discharged for wrapping.

Such conveyers usually include endless traveling elements in the form of a belt or chain arranged in pairs one above the other in a horizontal plane. A disadvantage in this form of apparatus is the belt may stretch and become loose and a chain, if used, may loosen through wear and become noisy. The object of the present invention is to provide means to maintain the traveling element taut, and more particularly to use the tightening means in connection with travelling elements made of flexible or resilient material.

In accordance with the present invention, the slice conveyer comprises, in combination, two superposed, traveling belts of flexible material, members interconnecting the belts and supporting prongs on which to impale the slices, and means for maintaining the tension of the belts constant, in spite of the stretching or wearing of the belts. Preferably, the belts, and grooves in the pulleys for their reception, are trapezoidal in cross-section. The members supporting the prongs may consist of bars which are set back from the periphery of the belts for the purpose of insuring that the distance between the extremities of the prongs supported by adjacent members remains constant, as hereinafter explained.

In a preferred construction, the belts partly wrap a pair of driven pulleys and a pair of freely rotatable pulleys which latter are urged, by a spring or equivalent means, away from said driven pulleys in order to exert a predetermined tension on both belts simultaneously. The spring, or equivalent means, may act on the freely rotatable pulleys through mechanism so contrived that, by displacing a hand member, the said pulleys are shifted and the belts and prong supports thereby permitted to be straightway removed bodily from the machine.

One embodiment of the invention is illustrated, by way of example, in the accompanying drawings whereon—

Fig. 1 is a sectional elevation of a conveyer shown applied to a slicing machine;

Fig. 2 is a plan, partly in section, corresponding to Fig. 1; and

Figs. 3 and 4 are detail sectional views, drawn to a larger scale, showing certain of the working parts in different positions.

The slicing machine shown in the drawings comprises the usual base 1, rotary knife 2, substance-supporting carriage 3 and fly-wheel 4, the carriage 3 being adapted to be reciprocated along guides 5, 6 on the base 1 by rotation of the fly-wheel 4, through the intermediary of the usual well-known crank and connecting rod mechanism.

The conveyer comprises a superposed pair of parallel rubber belts 11, 12 interconnected by a series of vertical bars 13 (two only being shown in Fig. 1), each of which bars 13 supports a row of outwardly projecting prongs 14 on which the slices, as they are cut, are impaled in known manner. Each bar 13 is set back inwardly from the periphery of the belts 11, 12, where indicated by the numeral 15, and is formed with upwardly and downwardly projecting lugs 16 and 17 secured by bolts 18 to the belts. The fact that the bars 13 are set back in this fashion insures that the distance between the extremities of the prongs of one row and those of the prongs of the adjacent row is the same when the belts are passing around the pulleys 31, 32 and 37, 38, hereinafter referred to, as when they are passing straight from pulley to pulley.

The conveyer proper (i. e. the parts 11, 12, 13 and 14) is positioned between upper and lower horizontal plates 19, 20 which are interconnected and maintained rigidly in spaced co-relationship, by a central pillar 21 riveted to the plates 19, 20. The lower plate 20 rests upon a bracket 22 outstanding from the base 1, the entire structure 19, 20 and 21 being removably secured to the bracket 22 by a nut 23 screw-threaded on a stud 24 projecting downward through the plate 20 and bracket 22 from the pillar 21.

Extending between the two plates 19, 20 are two vertical shafts 25 and 26 disposed one on each side of the pillar 21. The shaft 25 is rotatably mounted in ball bearings 27, 28 fitted in sockets 29, 30 in the plates 19, 20, and has secured to it, near its ends, two pulleys 31, 32. The shaft 26 is not rotatable, and is fitted at its ends into blocks 33, 34 which are slidably mounted in guideways 35, 36 in the plates 19, 20. Two pulleys 37, 38 are rotatably mounted on ball bearings 39 (one only being shown) fitted to the shaft 26 near its ends. The pulleys 31 and 37 are wrapped by the belt 11, and the pulleys 32 and 38 are wrapped by the belt 12. As shown, the belts and the grooves for their reception in the pulleys are trapezoidal in cross-section in order to avoid wear between the belts and their grooves.

In order to maintain the belts 11, 12 properly tensioned, the pulleys 37, 38 are normally urged away from the pulleys 31, 32 by the action of a tension spring 41, which is anchored to a pin 42 near the foot of the pillar 21 and is connected to the free end of one arm 43 of a bell crank lever 43, 44, fulcrumed at 45 on the pillar 21. The other arm 44 of the bell crank lever carries a roller 46 which co-operates with one end of a bar 47, the other end of which is pivotally connected at 48 to the shaft 26. The bar 47 is supported by a bracket 49 on the pillar 21, the bracket 49 serving also as an abutment for the toe 50 (see Figs. 3 and 4) of a hand lever 51, pivotally connected at 52 to an extension 53 of the bar 47. The hand lever 51 is adapted to co-operate with a pin 54 at the free end of the extension 53. The hand lever 51 extends through a gate 55 in the upper plate 19.

The normal working position of the parts is shown clearly in Fig. 3. In this position, the roller 46 bears against the adjacent end face 47' of the bar 47 and urges the bar together with the pulleys 37, 38 away from the pulleys 31, 32, thereby causing the belts 11, 12 to be tensioned. By moving the hand lever 51 to the left (i. e. into the position shown in Fig. 4), the hand lever fulcrums about its toe 50 and displaces the bar 47 to the left. The roller 46 is also displaced to the left and, at the same time, rides downward over the end face 47' of the bar 47 until, finally, it leaves the face 47', and bears against the lower face 56 of the bar. In this position of the roller 46, the spring 41 is totally inoperative as regards its function of imparting to the bar 47 an axial thrust. The bar 47 can now be withdrawn freely toward the left by continuing the movement of the hand lever 51 to the left-hand of the gate 55, the hand lever contacting with the pin 54 so that the hand lever and the bar move solidly as one body. By reason of the slidable mounting of the blocks 33, 34 in the plates 19, 20, when the hand

lever 51 is moved to the left, the blocks 33, 34 and the pulleys 37, 38 move freely in conjunction with the bar 47. Should the hand lever be so moved, the conveyer proper could straightway be removed from the pulleys and lifted clear of the machine for cleaning, inspection or repair.

A roller 56, journaled on a bracket 57 on the pillar 21, may be provided in order to enable the bar 47 to be easily withdrawn in spite of the upthrust thereon of the roller 46 acting under the tension of the spring 41. Both rollers 46 and 56 may be mounted on ball bearings.

The conveyer is arranged to operate in a well-known manner, the shaft 25 being intermittently rotated from the reciprocatory carriage 3 through the agency of a train of mechanism comprising a rack 58 on the carriage 3, a pinion 59 meshing with the rack 58, a pinion 60 rigidly connected to the same spindle as the pinion 59 and a spur-wheel 61 meshing with the pinion 60, the spur-wheel 61 being secured to the shaft 25.

If desired, in lieu of securing the prong-carrying bars 13 to two separate belts, the belts and the bars may be formed as a unitary structure.

The embodiment of the invention shown has been chosen simply by way of example, and it will be obvious that many modifications could be made in the constructional details without departing from the scope of the invention.

I claim:

1. A slice conveyer for slicing machines comprising in combination; a pair of spaced flexible traveling elements, slice-engaging means connecting said elements, pulleys around which said elements are guided, a pair of spaced supports upon which said pulleys are mounted, a pair of spaced plates, each plate being disposed at the opposite ends of said supports, aligned guides at one end of each plate in which the opposite ends of one of said supports are slidably received, the ends of said other support being mounted in the other ends of said plates, a spacing member connecting said plates, and spring-operated means mounted on said spacing member and connected with said slidably mounted support to urge said support away from said spacing member and maintain said traveling element taut.

2. A slice conveyer for slicing machines comprising in combination; a traveling element, slice-engaging means carried by said traveling element; spaced pulleys around which said traveling element is guided, a mounting for each of said pulleys, one of said mountings being stationary and the other movable; a supporting member having a lever pivoted thereto, a connecting means extending from said movable mounting to a position adjacent said lever, a spring

5 attached to one arm of said lever tending to swing said lever around its pivot, the other arm of said lever being operatively associated with said connecting member to urge said movable mounting away from said stationary mounting to maintain said traveling element taut.

10 3. A slice conveyer for slicing machines comprising in combination; a traveling element, slice-engaging means carried by said traveling element; spaced pulleys around which said traveling element is guided, a mounting for each of said pulleys, one of said mountings being stationary and the other movable; a supporting structure having a lever pivoted thereto, a connecting member attached to said movable mounting and slidably supported on said supporting structure adjacent said lever, a spring connected to one arm of said lever tending to swing said lever about its pivot, the other end of said lever engaging said connecting member to exert pressure on said movable mounting to maintain said traveling element taut.

15 4. A slice conveyer for slicing machines comprising in combination; a traveling element, slice-engaging means carried by said traveling element; spaced pulleys around which said traveling element is guided, a mounting for each of said pulleys, one of said mountings being stationary and the other movable; a supporting structure having a lever pivoted thereto, a connecting member attached to said movable mounting and slidably supported on said supporting structure adjacent said lever, a spring connected to one arm of said lever tending to swing said lever about its pivot, the other end of said lever engaging said connecting member to exert pressure on said movable mounting to maintain said traveling element taut, and a hand member operative to slacken said flexible element, said hand member comprising a lever pivoted on said connecting member and having a toe portion engaging said supporting structure.

20 5. A slice conveyer for slicing machines comprising in combination; a traveling element, slice-engaging means carried by said traveling element; spaced pulleys around which said traveling element is guided, one pulley having a movable and the other a stationary mounting, a supporting structure having a lever pivoted thereto, a connecting member attached to said movable mounting and slidably supported on said supporting structure adjacent said lever, said connecting member including a horizontal portion and an upturned end, a stop member on said upturned end; a spring connected to one arm of said lever tending to swing said lever about its pivot, the other end of said lever engaging said upturned end to exert pressure on said movable mounting to maintain said traveling element taut, and a hand lever piv-

oted to said upturned end of said connecting member, said hand lever having a toe portion engaging said supporting structure.

25 6. A slice conveyer for slicing machines comprising in combination; a traveling element, slice-engaging means carried by said traveling element; spaced pulleys around which said traveling element is guided, one pulley having a movable and the other a stationary mounting, a supporting structure having a lever pivoted thereto, a connecting member attached to said movable mounting and slidably supported on said supporting structure adjacent said lever, said connecting member including a horizontal portion and an upturned end, a stop member on said upturned end; a spring connected to one arm of said lever tending to swing said lever about its pivot, the other end of said lever engaging said upturned end to exert pressure on said movable mounting to maintain said traveling element taut, and a hand lever pivoted to said upturned end of said connecting member, said hand lever having a toe portion engaging said supporting structure, said first-mentioned lever being adapted to press against the horizontal portion of said connecting member when said connecting member is retracted and serving to lock said connecting member in retracted position.

30 7. A slice conveyer for slicing machines comprising in combination; a traveling element, slice-engaging means carried by said traveling element; spaced pulleys around which said traveling element is guided, a mounting for each of said pulleys, one of said mountings being stationary and the other movable; a supporting structure having a spring-actuated means mounted thereon, a connecting member extending from said movable mounting to a position adjacent said spring-actuated means, said spring-actuated means being adapted to bear against said connecting member to maintain said traveling element taut.

35 8. A slice conveyer for slicing machines comprising in combination; a traveling element, slice-engaging means carried by said traveling element; spaced pulleys around which said traveling element is guided, a mounting for each of said pulleys, one of said mountings being stationary and the other movable; a supporting structure having a spring-actuated means mounted thereon, a connecting member extending from said movable mounting to a position adjacent said spring-actuated means, said spring-actuated means being adapted to bear against said connecting member to maintain said traveling element taut, and a hand lever on said connecting member having a toe portion adapted to engage said supporting structure to retract said connecting member against the action of said spring-actuated means.

40 9. A slice conveyer for slicing machines

comprising in combination; a pair of pulleys, one movably and the other stationarily mounted, a flexible resilient band connecting said pulleys and exerting a tension tending to draw said pulleys together, a slice-engaging means carried by said band, and means connected with said movably mounted pulley tending to resist the tension exerted by said band and maintain said band taut.

10. A slice conveyer for slicing machines comprising in combination; a pair of pulleys, one movably and the other stationarily mounted, a flexible resilient band connecting 5 said pulleys and exerting a tension tending to draw said pulleys together, slice-engaging means carried by said band, and spring-actuated means associated with said movably mounted pulley tending to resist the tension 15 exerted by said band and maintain said band taut.

11. A slice conveyer for slicing machines comprising in combination; a pair of spaced supports, a pair of spaced pulleys on each 20 of said supports; one of said supports being movable and the other stationary; a traveling element connecting said pulleys; slice-engaging means carried by said traveling element; a plate disposed at the opposite ends 25 of said supports; a spacing member connecting said plates; said plates having at one end aligned guides in which the opposite ends of one of said supports are slidably mounted, the other of said supports being mounted in 30 the other ends of said plates; a bell crank lever pivoted on said spacing member, a spring tending to rotate said lever on its pivot, a roller on one end of said lever; a bar having an upturned end attached to said 35 movable support and slidably mounted on said spacing member, said roller normally tending to bear against said upturned end to maintain said traveling element taut, a hand lever extending through one of said plates 40 pivoted on said upturned end of said bar; said lever having a toe portion adapted to contact with a stationary element and force said bar toward said stationary support when said hand lever is swung, said bar being adapted to ride over said roller and turn 45 said bell crank against the tension of said spring.

In testimony whereof I have signed my name to this specification on this 31st day of 50 May A. D. 1928.

CORNELIS F. M. VAN BERKEL.
